UNITED STATES PATENT OFFICE.

MILARD GARFIELD GUTHRIE, OF WICHITA, KANSAS.

ACTUATING DEVICE FOR TEMPER-SCREWS.

1,368,394.

Specification of Letters Patent. Patented Feb. 15, 1921.

Application filed March 12, 1920. Serial No. 365,261.

To all whom it may concern:

Be it known that I, MILARD GARFIELD GUTHRIE, a citizen of the United States, and a resident of Wichita, in the county of 5 Sedgwick and State of Kansas, have invented certain new and useful Improvements in Actuating Devices for Temper-Screws, of which the following is a specification.

10 My invention relates to temper screws used in the drilling of wells and more particularly to a device for actuating the same. In the adjusting of temper screws serious injuries have been inflicted on the operators 15 by reason of the fact that in the normal operation of a drill cable it continually twists first in one direction and then the other imparting a similar movement to the temper screw which in turn causes a jerking or lateral movement of the rod or pole 20 usually employed for adjusting the temper screw there being a rigid connection between the pole and screw. As the operator pushes the pole around a temper screw in 25 effecting its adjustment, the pole when jerked in the direction of the operator is liable to strike the operator with great force, thus rendering the operation extremely dangerous.

30 It is the purpose of my invention to eliminate that danger by providing a device which prevents the jerking movement of the pole in the direction of the operator, while at the same time locking the pole to the 35 temper screw in its forward movement so that the proper adjustment can be effected.

I will describe one form of device embodying my invention and will then point out the novel features in claims.

40 In the accompanying drawings:

Figure 1 is a view showing in side elevation part of a temper screw having applied thereto one form of actuating device embodying my invention.

45 Fig. 2 is a top plan view of the device.

Fig. 3 is an enlarged detail view of the device shown in Fig. 1.

50 Figs. 4 to 7 are detail views of certain parts of the device shown in the preceding views.

Similar reference characters refer to similar parts in each of the several views.

Referring specifically to the drawings and 55 particularly to Fig. 1, the temper screw here shown is of standard construction, the same comprising a sleeve S threaded internally to

receive a screw threaded shank H which is formed at its lower end with an eye G, to which the drill cable C is connected.

The actuating device for this temper screw comprises a collar K carrying set screws A for securing the collar to the sleeve S as will be hereinafter described. At a point intermediate its ends, the collar K carries a ratchet wheel W which is integrally formed with the collar or keyed thereto so that the two move together. The detailed construction of the ratchet wheel is clearly shown in Fig. 4. Rotatably mounted upon the collar K at a point below the ratchet wheel W is an actuating member 60 designated generally at M, such member in the present instance comprising, as shown in Fig. 5, a yoke 15 provided with an opening 15^a for the reception of the collar K. 65 The yoke 15 is provided with tapered end portions 15^b and integrally formed with such portions are sockets 16 and 16^a designed for the reception of poles P and P' respectively, as shown in Fig. 1. As shown 70 in Fig. 3, the actuating member M is confined upon the collar K by a ring R, such ring being secured to the lower end of the collar by a plurality of bolts B. The detailed construction of the ring R is clearly 75 shown in Fig. 6 wherein it will be seen that such ring is flat and of such diameter that when in its applied position upon the collar its periphery will project beyond the periphery of the collar and thus serve to 80 confine the yoke 15 thereon.

As shown in Figs. 2 and 3, one tapered end portion 15^b of the yoke 15 carries a pair of posts 17 and 17^a connected at their upper ends by a plate 18. Pivotaly mounted 85 upon the posts 17 and 17^a are pawls L and L', respectively. These pawls L and L' are capable of occupying a locking position wherein they engage the teeth of the ratchet wheel W to cause the actuating member and ratchet wheel to move together, and a releasing position wherein the actuating member moves independently of the ratchet wheel. To lock the pawls in either of these 90 positions, I provide each pawl with a locking pin 19 or 19^a which is adapted to engage recesses 20 formed in the tapered portion 15^b as illustrated to advantage in Fig. 7. Each locking pin 19 is urged downwardly by a spring 21 mounted within a sleeve 22 95 and through which the pin is adapted to slide, such pin being provided with a collar 100

110

23 against which the spring bears and forces the pin downwardly. The detailed construction of these parts is clearly shown in Fig. 7.

5 By virtue of this arrangement it will be seen that when the pawls L and L' occupy such positions that the pins 19 and 19^a are in registration with any of the recesses 20, the springs 21 will automatically force the 10 pins into the openings thereby effecting a locking of the pawls. In the present instance, the recesses 20 are so arranged and of such a number as to effect a locking of the pawls in releasing and locking positions 15 so that by manipulating the pins either one or the other of the pawls may be caused to engage or disengage the teeth of the ratchet wheel W.

In operation, the operator grips one of 20 the poles P or P' and by traveling around the temper screw effects a rotation of the actuating member about the collar K as a center. For the sake of description let us assume that the pawl L' is locked in the 25 releasing position while the pawl L occupies a locking position in which it engages the teeth of the ratchet wheel W. Now by rotating the actuating member in a counter-clockwise direction as when viewed in Fig. 30 2, it will be seen that the actuating member is locked to the ratchet wheel, and the collar K being locked to the sleeve S through the medium of the set screws A, it is obvious that a rotation of the sleeve S will be 35 effected to adjust the shank H. Now should the collar K be jerked in the direction of the operator under the twisting action of the cable C as has been previously explained, the pawl L under the retrograde 40 movement of the ratchet wheel W will be drawn out of engagement with the latter thereby disconnecting the actuating member from the ratchet wheel and thereby preventing the actuating member from being 45 thrown in the direction of the operator. When the pawl L is thrown out of engagement with the ratchet wheel W it is moved to such a position that its pin 19 moves into one of the recesses 20 and thereby locks the 50 pawl in its releasing position.

Although I have herein shown and described only one form of device embodying my invention, it is to be understood that various changes and modifications may be 55 made herein without departing from the

spirit of the invention or the spirit and scope of the appended claims.

What I claim is:

1. A device of the character described comprising, a collar, set screws carried by 60 the collar, a ratchet wheel fixed to the collar, an actuating member comprising, a yoke loosely embracing the collar, sockets formed on the yoke for the reception of poles, a ring detachably secured to the 65 sleeve for confining the yoke thereon, pawls pivoted on said yoke and capable of occupying a locking position wherein they engage the teeth of said ratchet wheel and a releasing position wherein they disengage 70 the ratchet wheel, and spring pressed pins carried by said pawls and engageable with said yoke for locking the pawls in releasing or locking position.

2. In combination, a temper screw, a 75 member for rotating the temper screw in either direction, and means interposed between the screw and member for operatively connecting the two when the member is moved in one direction or the other and for 80 disconnecting the two when the temper screw is moved in a direction opposite to the movement of the member.

3. In combination, a temper screw, a 85 member for rotating the temper screw, and pawl and ratchet wheel interposed between the screw and member for operatively connecting the two when the member is moved in one direction and for disconnecting the two when the temper screw is moved in the 90 direction opposite to the direction of movement of the member.

4. A device of the character described comprising, a collar, an actuating member rotatably mounted on the collar, a ratchet 95 wheel fixed to the collar, pawls pivoted to the actuating member, and means for locking the pawls in predetermined positions for the purpose described.

5. A device of the character described 100 comprising, a collar, a ratchet wheel fixed to the collar, an actuating member rotatably mounted upon the collar and openings formed therein, reversely disposed pawls pivoted on the member, and spring pressed 105 locking pins carried by said pawls and engageable with the walls of said openings for locking the pawls in predetermined positions.

MILARD GARFIELD GUTHRIE.
